PRESSED STEEL CAR END

John P. Gallagher, Jersey City, N. J.

Application September 22, 1932, Serial No. 634,346

28 Claims. (Cl. 105—410)

The invention relates in general to a pressed metal panel for use in those parts of a railroad car construction which are subjected to load pressures and other stresses which tend to distort the same, and the invention specifically relates to a pressed steel panel which constitutes one of a set of similar panels, or which constitutes a single panel for forming a portion of or an entire wall of a railroad or similar car construction.

More specifically defined, the invention relates to a pressed steel car end or car side of a freight, a box, a gondola, or a hopper car, and which ends and sides will be referred to herein-after collectively as car walls.

It is known in the art of pressed steel car ends to form them of one or more sections of corrugated sheets of metal with the sections extending vertically as well as horizontally. In these known forms the corrugations extend in closely positioned groups and with the corrugations extending parallel to each other, either vertically or horizontally. When heavily loaded and exposed to the shocks incidental to the usual service conditions to which cars of this character are subjected, stresses are set up in these known forms of car ends, the stresses being localized at a point somewhere about midway between the vertical edges and about one quarter to one third up from the bottom line and usually in the vertical medial plane of the car end and diverge therefrom principally downwardly and outwardly towards the lower edge. In the case of the car ends with the vertically disposed corrugations, these strains act to belly or bulge the central portion of the car end outwardly in a curve about the vertical medial line. In the case of car ends with the corrugations extending horizontally, there is a similar outward bulging of the car ends about some horizontal line, usually about a line positioned approximately one quarter to one-third of the height of the car end, measured from the lower edge. As the lower edge is usually fastened to a rugged end sill, the car end thus tends to turn about its lower edge.

It has been found, however, that the usual collision shock on any form of steel end car acts to cause it to twist out of its normal plane and about some diagonal line. For the purpose of counteracting this tendency to distort, it has been known to provide diagonal struts which extend from the region adjacent the center sills towards outer, upper edges of the car end. To a certain extent this same condition exists with

reference to the car sides and this outward bellying or bulging of the sides becomes particularly noticeable in the case of open top cars in the absence of the bracing effect provided by the roof. In the case of corrugated car ends now known repeated shocks tend eventually to cause the corrugations to flatten out as the car end as a whole bulges horizontally or vertically as above described and in this way these car ends eventually become simply more or less flat walls without any self-reinforcing features.

In addition to the car walls, certain other structural parts of the car which do not extend strictly in a vertical direction, such as the drop doors of gondola and hopper cars, are likewise subjected in actual use to distorting strain and require the addition thereto of stiffening and reinforcing members disposed to resist the distortion of the structural parts from its original confirmation.

The primary object of the invention is to provide a simple, easily formed, one-piece rugged structural unit or panel which can be made of sheet metal corrugated and bent to provide an integral self-contained, reinforcing truss construction, and which integral reinforcement will tend to resist or at least minimize deflections or bendings of the unit when subjected to the usual distorting stresses to which structural parts of railroad cars are subjected while in use.

Broadly, this object of the invention is attained by providing a corrugated panel construction in which the corrugations are arranged in the form of a system of single triangular units, sometimes hereinafter referred to as endless triangular beams, or multiple of such system of continuous beam units organized to resist bendings of the panel in all directions. In the case of the pressed steel car end embodiment of the invention herein illustrated this object is attained by incorporating in a single thin steel panel, vertical and horizontal types of corrugations arranged and disposed so as to be accommodated in the single sheet without functionally interfering with each other, and likewise to include therewith diagonally disposed corrugations to form diagonal struts organized and arranged particularly to resist distortions or twistings of the car wall about the diagonal lines above discussed.

Another object of the invention is to provide a panel wall construction in which the panels in and of themselves will provide the necessary vertical, horizontal and diagonal brace elements usually found in fabricated car constructions, thus

5

featuring an elimination of the usual posts and wall girders.

Still another object of the invention is to provide an improved form of car wall which can be formed of a multiple of panels and which panels of themselves will provide vertically extending posts or lines of reinforced area through which roof strains can be transmitted directly to the car body underframe in those cases where a roof is provided and which will coat with horizontally extending corrugations at the top of the side walls to provide a rugged skeleton frame work for maintaining the car body parts rigid relative to each other, even in the absence of the roof structure.

The present disclosure features a panel construction in which operative stresses imposed thereon are transmitted downwardly to the end or side sill to which it is fastened while eliminating or at least minimizing any tendency of the panel or any part thereof to become distorted from its original configuration.

Still another object of the invention is to provide part of a panel side or wall construction with reinforcing post-forming-corrugations designed to receive the wooden furring strips for supporting the wooden lining used in certain cars of this character.

Various other objects and advantages of the invention will be in part obvious from an inspection of the accompanying drawings and in part will be more fully set forth in the following particular description of one form of mechanism embodying the invention, and the invention also consists in certain new and novel features of construction and combination of parts hereinafter set forth and claimed.

In the accompanying drawings:

Fig. 1 is a view in elevation of the outside of a box car showing a steel end formed of three panels each constituting a physical embodiment of the invention, it being understood that in actual construction the three panels will be alike, but it is within the scope of this disclosure to use one of the three panel forms illustrated, for instance the central panel alone may be used and the two outside panels entirely omitted, or their place taken by the usual wooden sheathing, by a flat uncorrugated plate, or by a conventional form of corrugated plate or panel;

Fig. 2 is a horizontal sectional view taken on the line 2—2 of Fig. 1 looking downwardly as indicated by the arrows;

Fig. 3 is a vertical sectional view taken along the longitudinal medial plane of the car and taken on the line 3—3 of Fig. 1; and

Figs. 4, 5, 6, 7 and 8 are each transverse sectional views taken respectively along the lines 4—4, 5—5, 6—6, 7—7, and 8—8 of Fig. 1.

In the following description, reference will be made particularly to the car end illustrated but it will be understood that the structure described and illustrated will be equally applicable, except for variations in dimensions and other obvious changes, to a car side and that the panel structure herein featured may be utilized in a car structure which has no roof, and that the walls may be inclined to the vertical as would be the case with a gondola or hopper car.

In the drawings there is disclosed a car body underframe 10 including a center sill 11, an end sill 12, a floor 13, a roof 14, represented by a roof sheet 15 and otherwise it is intended that the inventive features herein disclosed be illustrated

in connection with a car body of conventional form.

The car end 16 is formed of three substantially rectangular, upstanding panels, designated in Fig. 1 from left to right as 17, 18, and 19. The adjacent vertical edge portions 20 of the panels are disposed in lapped relation as shown in Fig. 2 and the lapped portions are secured together in each case by a line of rivets 21. This construction provides a length of double thickness 10 of material between the central panel 18 and the two lateral panels 17 and 19. This double line of reinforcement extends from the end sill 12 to the roof sheeting 15. The edge portions 20 are substantially flat as shown in Figs. 4, 5, and 6 or 15 may be slightly curved to form in their coacting relation a U shaped channel as shown at 22 in Fig. 2. The outer vertical edge portions of the panels 17 and 19 are extended beyond the adjacent sides of the car and bent to form corner 20 flanges 23 which receive rivets 24 which fasten the flanges to the car side plates 25.

The bottom edge portions of the panels are bent slightly outward as shown in Fig. 3 from the plane of the major portion of the panel to 25 form end sill engaging flanges 26 which are secured to the end sill 12 by means of rivets 27, somewhat following conventional practices in this respect. The upper portions of the panels above the corrugations hereinafter described are 30 flat as indicated at 28 and at their extreme upper edges are bent to form roof engaging flanges 29 underlapping and secured to the roof sheet 15 by rivets 30.

In spaced relation inwardly from the outlining edges of each of the panels is a reinforced area composed of intercommunicating corrugations formed by subjecting the initially flat plate to a pressing operation with suitably formed dies. The corrugations are for the most part relatively 40 long channels, U-shaped in cross section with the troughs of the channels facing inwardly of the car, and the channels themselves projecting outwardly of the remaining flat or substantially flat portion of the plate. While the panels herein 45 illustrated are for the most part flat plates, it is obviously within the scope of the disclosure to curve these plates wherever necessary as in curved wall or bottom structures. It is also obvious that the panel structure herein featured 50 may be bent to form a corner or other angled part of the car structure.

The design of corrugations disclosed includes adjacent the edge portion 20 two transversely spaced apart uprights or vertically disposed corrugations 31 and 32 which extend upwardly for any desired distance and constitute hollow posts which tend to resist buckling or outward bellying of the panels about horizontal lines. In the form of the invention disclosed 60 in connection with the central panel 18 the posts are connected at top and bottom by means of horizontally disposed corrugations 33 and 34 which form horizontally disposed struts disposed to resist buckling about vertical lines and coat 65 with the posts to form a substantially rectangular frame and which corrugated frame extends almost to the roof sheet 15. In the case of the panels 17 and 19 the upper horizontal channel is omitted but may be added if a little more reinforcement is needed in the upper region of the 70 reinforced area.

Disposed within the outline of this rectangular frame are diagonal corrugations intersecting each other at right angles and open at their ends 75

to the corrugations 31 and 32 forming posts. These diagonal corrugations form diagonal braces or struts and coact with the corrugations 31-32 at their ends mutually to reinforce each other. Certain of these diagonal corrugations such as those designated 35 extend from the upper left to the lower right hand side and others marked 36 extend from the upper right to the lower left side of the X-shaped design formed thereby. From this construction it is seen that the diagonal braces or struts merge at their ends either into the vertical corrugations or into the horizontal corrugations.

It will be noted from the showing in Fig. 1 that these corrugations form a pattern which is a duplicate in whole or in part of a unit configuration comprising four sets of corrugations. The corrugations of each set extend parallel to each other and are spaced apart a distance greater than their width to provide flat areas therebetween. The corrugations of one set, such as 31-32 extend vertically; those of another set, such as 33-34 extend horizontally; those of a third set, such as 35-36, extend diagonally downward from left to right; and those of a fourth set, such as 36-36, extend diagonally downward from right to left. As the diagonal corrugations 35 and 36 intersect each other, they form between them horizontally spaced apart flat triangular areas 37 and 38 and vertically spaced flat double triangular or rectangular areas 39 and 40 with the points or right angled corners of these areas spaced equidistant from a point of reference 41 at the central point of intersection of the corrugations 35 and 36. Positioned within each of the areas 39 and 40 is a bullseye or pan-like form of corrugation 42 somewhat parabolic in axial cross section with a slightly flat crown and the axis of this protuberance 42 measured along the line a-a is relatively short, i. e. less than its maximum diameter. In general it will be understood that the corrugated reinforcing design as shown in panels 18 and 19 is a duplication of the unit shown in panel 17. In the unit structure there are shown grooves 31 and 32, centrally positioned cylinder or pan 42 and half lengths of 35 and 36 disposed in the form of a square connected end to end and arranged concentric with the axis a-a of the cylinder 42 and with the annular portions 40 and triangular portions 37 and 38 disposed in a common plane.

In car wall constructions of the type under discussion there is very little, if any, bending of the panels in their upper portions and therefore there is no particular need of providing for any special reinforcing of the upper portion of the panel. For this reason the upper portion of the panel 19 is shown flat at 28 for the upper third of the panel. As noted above in such structures the loci of the points of thrust of the load which tends to bend the panel is about one-quarter to one-third up from the bottom, or approximately along the line a-a. It is therefore suggested in the case of the right panel 19 that the upper third of the reinforcement shown in the central panel be omitted.

In the showing of the left hand panel 17, the reinforced area has been still further curtailed and the reinforcement confined to the lower third of the panel where it is most needed, so that in this suggested form the car wall is for the most part a flat, uncorrugated sheet of metal and with a small amount of reinforcing corrugation localized where it will do the most good to meet the strains

usually imposed upon the car ends. It is obvious that the space 28 may be utilized to contain windows and other openings or may be utilized for other purposes.

The present construction with its formation of inwardly facing hollow posts 31 and 32, lends itself admirably to receive vertically disposed wood furring strips 43, to the inner faces of which is secured a wood lining 44 herein shown to be the conventional tongue and groove boards 45 disposed in horizontally extending lengths in accordance with approved practice. In those cases where the boards extend vertically the furring strips may be contained in the horizontal corrugations 33 and 34 or in either case may be contained in one or more of the diagonal corrugations.

While the posts 31 and 32 may extend almost to the top of the panel as shown in the case of the middle panel 18, and as shown in Fig. 3, it is herein suggested that these posts forming corrugations be of less height and may terminate at and merge into the upper ends of the corrugations 36-36 defining the upper end of the corrugated portion of panel 19, or may extend above the corrugated portion for any desired or required distance as indicated in the case of the panel 17.

It will be further understood that the panel as herein disclosed may be utilized as a repair part of a conventional box car now in general use, and in which case one of the panels of the type herein disclosed is positioned where it will be of the maximum value and, in the case of a car end, is usually centrally positioned, as is the panel 18.

It is to be understood that in place of the three-panel type of pressed steel end herein disclosed, the entire end may be made of a single sheet pressed to form and in which case, of course, the lapped joint structure at 22 will be omitted. It is also suggested that in those cases where there is no particular need for providing rigidity to the upper portion of the wall, the lower portion may be formed of a single sheet provided with the vertical, horizontal and diagonal reinforcing grooves herein featured leaving the upper portion as a flat sheet panel. As the usual distortion is along the diagonal lines corresponding to the direction of the members 35 and 36, it is herein suggested that a simpler construction may be provided by utilizing the integral diagonal braces herein disclosed, omitting either or both of the vertical and horizontally extending corrugations. It is also obvious that the diagonal corrugations may extend from adjacent the center sill and diverge upwardly and outwardly towards the opposite upper corners as is usual with the separate diagonal braces now in general use for reinforcing wooden and other forms of car ends.

A panel of the character shown in the case of panel 18 when horizontally disposed is particularly adaptable to form the side or end of a gondola or other forms of open top car. In this case the length will extend horizontally instead of vertically as in the illustrated case; the channels 33-34 will extend vertically forming short posts corresponding to the posts 31-32 and the long channels 31-32 will extend horizontally and form long girders at the top and bottom of the gondola car wall. In any such case the upper edge will be finished in any conventional way as by rolling it into a bead or by securing it to a top channel by the usual channel rivets.

By means of the disposition of the corrugations

herein disclosed in their vertical, horizontal and diagonally inclined relations, it is possible to provide a cheap panel structure which can be easily pressed or stamped to shape, which can be used 5 alone or assembled with other panels to form an integrally braced structure without necessity of providing separate bracing elements thus economizing in both the cost of material and in the labor charges incidental to fabricating the main 10 structural part with its reinforcing additional parts. A car wall, and particularly a car end of the character herein disclosed, provides all of the resistance to bending about vertical and horizontal axes such as are provided by known structures, and in addition thereto provides, without 15 additional material, a structure which will tend to resist the more prevalent diagonal twists to which cars, and particularly freight cars are subjected during starting and stopping and other 20 shocks.

I claim:

1. An upright structural part of a car body adapted to resist loads imposed thereon in a horizontal direction, and which loads are usually 25 localized at a point thereon intermediate its upper and lower edges, said structural part comprising a one-piece sheet of metal provided in spaced relation to its outlining edges with long corrugations, substantially U-shaped in cross section 30 and forming vertical posts, other corrugations opening at their ends into and connecting the posts at top and bottom thereof to form horizontally extending struts and coacting with the posts to form a rectangular continuous reinforcing frame spaced inwardly from the outlining edges of the sheet, and certain other corrugations 35 positioned between and extending at an angle to the posts to form diagonal struts at opposite ends of the posts, intersecting each other to form an X located in the frame in spaced relation to one end of the frame.

2. A pressed metal panel constituting a part of a car construction, comprising a flat sheet formed with a plurality of projections extending integrally from one side thereof and spaced from 45 opposite outlining edges to leave the edge portions uncorrugated and adapted to receive fastening means, said projections arranged in a pattern which includes duplications of a unit configuration comprising a cylindrical pan-shaped element having an axial length measured perpendicular to the plane of the sheet less than its 50 diameter and four straight elements each U-shaped in cross section and of uniform cross-sectional configuration from end to end arranged as the sides of a square and connected end to end, said square being concentric with, encircling and spaced from the cylindrical element with the 55 portions of the panel between the cylindrical element and the square disposed in the plane of the flat edge portions.

3. A pressed metal panel constituting a part of a car construction comprising a flat sheet formed with a plurality of corrugations projecting integrally from one side thereof and spaced from opposite outlining edges to leave opposite edge portions flat and adapted to receive fastening means, said corrugations arranged in a pattern which includes duplications of a unit configuration comprising four projections arranged 65 symmetrically about a point of reference, each projection including a substantially flat right angled corner and all four corners spaced equidistant from said common point of reference and

arranged in pairs on opposite sides of said point and a side of each projection extending parallel to the contiguous side of the next adjacent projection, and the portions of the sheet between said projections contained in the plane of the opposite edge portions. 5

4. In a device of the class described, the combination of a pair of metal panels having vertically extending edges and disposed side by side to form a portion of a car body wall, each panel comprising a single pressed metal sheet corrugated in spaced relation to its vertically extending edges to form reinforcing members, certain of which extend vertically and certain other of which extend at an angle to the vertical, the 10 vertical reinforcing members constituting integral posts extending substantially from top to bottom of the panels, the adjacent vertical edges of said panels being flat and with flat sides secured together in lapping relation to form a 20 double thickness of metal constituting a vertically disposed stiffening member positioned between and extending parallel to the adjacent posts formed by the corrugations of the panels.

5. In a car body wall construction, the combination of a plurality of sheet metal panels disposed with their adjacent vertical edges lapping and secured together to form the wall, and to provide a line of double thickness of material extending vertically from top to bottom of the 30 wall, certain of said panels provided with integral vertically extending corrugations positioned on opposite sides of and extending parallel to said line and coacting therewith to form a series of 35 vertically extending reinforcements constituting hollow posts at opposite vertical edges to brace the wall from top to bottom at such edges, said posts having structural strength sufficient to provide the requisite rigidity of wall without the necessity of employing the usual car side or corner 40 posts and said panel provided with integral horizontally extending corrugations opening into and connecting respectively the tops and bottoms of said hollow corner posts.

6. A sheet metal car side unit corrugated to 45 form a series of triangular beams interconnected to form a single endless corrugation.

7. A sheet metal car body wall construction provided with corrugations forming a plurality of identical patterns, each of said patterns forming 50 an endless beam of substantially triangular form and certain of said beams opening into the next adjacent beam at their adjacent angles.

8. A sheet metal car end formed of a plurality of separate panels secured together, each panel 55 being of rectangular form and being corrugated with vertically and horizontally extending corrugations forming a rectangular outlining frame spaced a slight distance inwardly from the edges of the panel to leave an outlining flat fastening 60 flange and the portion of the panel within the frame being corrugated with diagonally extending corrugations opening at their ends into the sides of the frame and coacting therewith to provide a plurality of endless beams. 65

9. In a car wall construction, the combination of upstanding corner posts, a sheet metal construction having opposite upright edges flanged to provide a casing lapping two sides of each post, the lower portion of the construction being 70 corrugated to provide a reinforced area between the posts, the corrugations forming a line of reinforcing beams disposed close to each other and each beam being of triangular form with the three sides opening into each other end to end. 75

10. In a car wall having outwardly pressed reinforcing corrugations coacting to form an endless channel on the inner side of the wall, certain of said corrugations combined to form a plurality of horizontally spaced and vertically extending posts extending substantially the full height of the car wall, other corrugations extending horizontally, connecting the posts in pairs and constituting struts, and still other corrugations extending diagonally between the posts and mutually intersecting each other at their mid-lengths to form X-shaped braces between the posts.
11. A sheet metal car end corrugated to form vertical and horizontal corrugations connected end to end to form a rectangular frame, and also corrugated to form diagonal corrugations forming a lattice-work connection between opposite sides of said frame.
12. A metal panel constituting a unit of a car side provided with a plurality of interconnected corrugations, two of said corrugations extending parallel to each other, a third corrugation connecting and having its ends opening into said parallel corrugations and two other corrugations intersecting each other at their mid-portions to form an X, with one end of each of said X-forming corrugations opening into the parallel and third corrugations at their intersecting corners and having their opposite ends opening into the parallel corrugations in spaced relation to said corners.
13. A metal panel constituting a unit of a car side provided with four corrugations each of substantially uniform cross sectional form from end to end, arranged in the form of a square and each one opening at opposite ends into the adjacent corrugations to form an endless corrugation, and a fifth corrugation of substantially frusto-conical form disposed within the outline of the endless corrugation and spaced therefrom.
14. In a railroad car wall a rectangular panel having a flat outlining edge portion of substantially uniform width to form fastening flanges about the four edges of the panel, the area within said flat flanges being provided with corrugations, with the corrugations constituting duplicates of a single pattern including straight lengths connected at their ends into an endless design and having bull's eye projections formed between and spaced from certain of the straight length corrugations and with an uncorrugated area surrounding the projections.
15. A sheet metal car end provided with corrugations to form a reinforced area, with the corrugations disposed to form the area into a plurality of triangular endless corrugations with uncorrugated triangular areas within the endless triangular corrugations and a single corrugation common to two triangular endless corrugations.
16. A metal panel provided with a plurality of straight lengths of corrugations with four of said corrugations arranged in end to end relation and opening at their ends one into another to form a single rectangular endless corrugation, other of said corrugations extending diagonally between the corrugations forming the endless corrugation, said corrugations coacting to form a plurality of endless corrugations of triangular form with substantially flat, uncorrugated areas of triangular form between the triangular endless corrugations.
17. A metal panel provided with a plurality of straight lengths of corrugations with four of said corrugations arranged in end to end relation and opening at their ends one into another to form a single rectangular endless corrugation, other of said corrugations extending diagonally between the corrugations forming the endless corrugation, and said corrugations coacting to form a plurality of endless corrugations of triangular form.
18. A metal panel provided with a plurality of corrugations, two of said corrugations extending in parallel relation, a third corrugation extending between and having its opposite ends opening into the parallel corrugations and two other corrugations forming a V with their adjacent ends opening into said third corrugations and having their other ends opening into said parallel corrugations.
19. A metal panel provided with a plurality of straight corrugations, four of said corrugations being connected end to end to form a rectangular endless corrugation, four other diagonal corrugations having their opposite ends opening into the endless corrugation and forming two pairs, with the corrugations of each pair forming an X construction, said X constructions disposed with their adjacent ends opening into each other at their junction with the endless corrugation.
20. A rectangular sheet metal panel provided adjacent its four outlining edges with a continuous corrugation forming an integral reinforcing frame and said panel also provided within said frame with other straight corrugations extending in pairs, each pair forming a V extending uninterruptedly between different sides of the continuous corrugation and having their opposite ends opening into said continuous corrugation.
21. A metal panel provided with a reinforced area formed of straight lengths of corrugations, disposed in relative angular relation, with their channels opening at their ends into each other and coacting to form a plurality of triangular endless corrugations, said triangular endless corrugations being of different sizes and with a part of a larger triangle forming part of a smaller triangle.
22. A sheet metal panel forming a structural element for a car and provided with a plurality of corrugations, certain of said corrugations forming a plurality of spaced apart circular bull's eye projections and the other corrugations being straight of uniform cross-sectional configuration throughout their respective lengths and spaced from the bull's eye projections with an annular uncorrugated area surrounding each bull's eye projection and disposed between the same and the adjacent straight corrugations.
23. A metal panel provided with a plurality of straight corrugations, four of said corrugations being connected end to end to form a rectangular endless corrugation, four other diagonal corrugations having their opposite ends opening into the endless corrugation and forming two pairs, with the corrugations of each pair forming an X construction, said X constructions disposed with their adjacent ends opening into each other at their junction with the endless corrugation and a circular pan-like corrugation centered between and spaced from the two X constructions.
24. A car end constructed of sheet metal in which is formed a pan-like circular corrugation and the space about said corrugations provided with straight corrugations spaced from and thus

6
not intersecting the circular corrugation to leave a substantially flat uncorrugated area between the circular and straight corrugations.

25. In a car wall construction, a sheet metal unit having a pan-like form of corrugation spaced from its edges, said projection being approximately parabolic in axial cross section and having a substantially flat crown portion.

26. In a corrugated sheet of metal having four straight grooves formed integral and coacting to form a quadrilateral figure, and a pan-like form of corrugation centered in the space formed by said grooves, said pan-like corrugations being somewhat parabolic in axial cross section, with a slightly flat crown and having its axis less than its diameter.

27. A sheet of corrugated metal having straight grooves forming the corrugations and projecting to one side of the plane of the uncorrugated portions of the metal sheet, said grooves intercon-

nected to form a lattice effect, and in which certain of the grooves coact to form a continuous corrugation of triangular form.

28. A one-piece panel of sheet metal provided in spaced relation to its outlining edges with half-tube forms of corrugations interconnected to form a single endless channel, defining a substantially flat corrugated area, said area at every cross section thereof intercepting a reinforcing wall extending substantially perpendicular to the plane of the corrugated area thereby tending to resist bending of the sheet about all possible hinge lines, and said area containing an additional corrugation including an endless wall extending substantially at right angles to said plane and the portion of the panel surrounding said additional corrugation being flat and uncorrugated.

JOHN P. GALLAGHER.
